HIGH FREQUENCY TUBE

Richard S. Briggs, Beverly, Mass., assignor to
Bruce A. Coffin, Peabody, Mass.

Application February 13, 1942, Serial No. 430,791

8 Claims. (Cl. 250—27.5)

This invention relates to a tube for use with so-called ultra-high frequency.

In the use of ultra-high frequency tubes in radio work it becomes highly important to shorten the lead of the elements from within the tube to their connection outside of the tube in order that the radio frequency transmission may be over as short a path as possible. In tubes already in use designed for this high frequency work leads are taken out through the walls of the envelope closest to the plate and grid in order to shorten these leads but in most instances the leads from the filaments or cathode filaments extend out through the stem or press and present a problem in shortening the leads for this element. To lead the filaments out through the side of the glass envelope, while the same may have been proposed, presents an expensive seal, especially when a plurality of conductors are used for this purpose, and is undesirable from the standpoint of practicability in the construction cost of a tube.

One of the objects of this invention is to leave the filament conductors in the stem press in a manner heretofore provided but to, in effect, nullify their high frequency carrying capacity by short-circuiting this high frequency current from a point just below the heating portion of the filament which is utilized.

Another object of this invention is to short-circuit the high frequency current through the glass of the tube envelope while leaving the envelope and the stem press with its filament lead therein in the customary manner found to be economical in manufacture.

Another object of the invention is to provide a high frequency path of low resistance for transmitting high frequency current out of the tube through the wall thereof to the ground rather than along the filament wires.

Another object of the invention is to utilize a capacity coupling which will conduct the high frequency current and provide less resistance where high frequencies are used than in a single or double lead wire from the filament.

Another object of the invention is to provide an arrangement which may be utilized with various forms of filaments or with various forms of plate and grid arrangement or numbers of plate and grid arrangements forming a plurality of other elements in the tube.

Another object of the invention is to provide a construction which may be utilized advantageously with a shield for the tube by affording

very short leads to a concentric line oscillating circuit which extends upwardly from the tube.

With these and other objects in view, the invention consists of certain novel features of construction, as will be more fully described and particularly pointed out in the appended claims.

In the accompanying drawings:

The figures are largely diagrammatic,

Fig. 1 illustrating in section the envelope, stem 10 press and parts contained within the envelope of my tube.

Fig. 2 is a similar view to Fig. 1, illustrating a slightly modified arrangement.

Fig. 3 is a section on line 3—3 of Fig. 2.

Fig. 4 is a view similar to Fig. 1 but showing a still different modification than shown in Fig. 2.

Fig. 5 is a view illustrating the arrangement shown in Fig. 1 but showing a slightly modified arrangement in the provision of a portion shown in Fig. 1 extended to provide a base.

Fig. 6 is a sectional view illustrating a still different modification and development which this invention is capable of.

In proceeding with this invention I have devoted attention primarily to the shortening of the lead over which the high frequency current from the filament is transmitted, and in accomplishing this I have utilized a capacitance with one of its plates attached to the filament within

30 the tube and the other plate attached to an external circuit without the tube, the spacing being such that the glass envelope is substantially equally distant from both plates. The condenser is in the form of concentric cylinders and provides a large number of paths radially outwardly from the filament for the transmission of high frequency current along a path of very low inductive reactance from about the filament so that in effect a very short lead for the high frequency

40 current from the filament is provided, and a short circuit is provided from the filament to the ground via the very low capacitative reactance of the condenser, rather than along the filament leads which are used for heating the filament.

45 The capacitative coupling obtained by the aforesaid manner is used as a low impedance cathode lead for the express purpose of carrying an ultra-high radio frequency cathode current. The filament or heater connections to the cathode are merely used to supply direct current or low frequency alternating current power to the cathode. These leads may have suitable chokes interposed to out keep radio frequency cathode currents and confine these currents to a path through the cathode shield to the outer electrode. In this

manner radio frequency cathode currents are effectively by-passed and need not travel through the filament or heater lead wires which may offer considerable impedance at ultra-high radio frequencies.

Although the drawings show application of the cathode shield to vacuum tube triodes, the use of the same may be generally applied to multi-element tubes where a common cathode lead is used. In the case of pentodes, it may be advantageous to connect the suppressor grid directly to the cathode shield, the latter serving a dual purpose by combining suppressor grid and cathode leads. The following is a more detailed description of the arrangement by which I accomplish this desired result.

I have illustrated in Figs. 1, 2, 3 and 4 merely the envelope and press portion without showing the base and studs usually mounted on the envelope, to which the leads are connected, while in Figs. 5 and 6 the base is shown with a certain modified concentric tube lead arrangement in the latter figure. In all these various figures the same numerals will be used in referring to the same or equivalent parts of the tube while the modifications will be pointed out with different reference numerals for the sake of descriptive clarity.

In the various figures the glass envelope or bulb 10 is sealed to the stem press 11 at substantially the location 12, at the lower portion of the envelope in a well known manner. An exhaust conduit 13 is sealed off as at 14 after the envelope has been exhausted. Support wires 15 and 16 are molded into the stem press 11 and extend upwardly into the envelope and, through means of insulating spacers 17 and 18, mount a plate 20 and a grid 21. The plate 20 is connected by means of tab 22 to a top terminal 23 extending through and sealed in the top wall of the envelope while the grid is connected by the tab 24 to the terminal 25, also extending through the top wall of the envelope as illustrated. The plate and grid may be mounted within the envelope by any suitable means, that shown being one conventional form which may be utilized, it being understood that the particular form of plate and grid mounting are not a part of this invention.

Within the envelope I have provided an inverted cuplike shield designated generally 26 and which consists of a cylindrical portion 27 located close to the glass envelope 10 and an end wall 28 which is attached to the support wires 15 and 16 at 29 and 30 whereby the cup is supported in desired position within the envelope. A mica spacing ring 27a may be positioned between the cylinder 27 and the glass envelope. A center metallic filament support 31 extends upwardly from the midpoint of the bottom wall 28 and passes through the spacers 18 and 17, and in firm frictional engagement therewith, to be supported thereby. The cathode filament 34 is attached as at 35 to the upper portion of this support 31 and extends downwardly in opposite helical paths spaced from the support 31 and passing through the openings 36 and 37 in the insulating spacer 18 and then through the openings 38 and 39 in the bottom wall 28, but out of contact therewith. The filament lead then continues through the press as at 40-41 to an external source for the application of heating power. In this manner the cathode filament is connected to the end wall 28 of the inner shield 26 through the center support post.

I have arranged a metal cylindrical member 42 outside of the envelope 10 and spaced from the envelope by an insulating spacer 43 and filling material such as mica so that the envelope 10 will be substantially midway between the cylindrical member 42 and the cylindrical portion 27 of the shield 26. The member 42 will have an axial extent at least as great as the axial extent of the cylindrical portion 27 of the shield 26. These spaced cylindrical surfaces provide a condenser or capacitance which is electrically connected to the cathode filament 34 at a location at the center of its heating portion 35, via supporting rod 31. This capacitance 15 serves as a low impedance short circuit for the high frequency current from the cathode filament to an external circuit through the wall 10 of the envelope. By reason of the cylindrical or circular arrangement of the plate of the condenser, a large or infinite number of paths for transmission of this high frequency current from the tube is provided. Thus low impedance is had and the effect of the short lead from the cathode is provided, the capacitative reactance in ohms 20 being known to be in accordance with the equation

$$x_c = \frac{1}{2\pi f c}$$

30 where f equals frequency in cycles per second and c equals capacity in farads.

Various arrangements of this capacitance which I have just described may be provided, and in Fig. 2 instead of providing an inner cylindrical shield designated 26 in Fig. 1 I have provided a divided inverted cup now designated in two parts 46 and 47, there being a substantially semi-cylindrical wall 48-49 with an end 50 for the semi-cylindrical part 48 and an end 51 for the semi-cylindrical part 49. These are each independently supported on support wires 15 and 16 as at 52 and 53 while the support wires extend completely through the stem press, their extensions being designated 15a and 16a. The filament support 54 is molded into the stem press 11 and extends upwardly in the space 45 between the two halves of the shield. The cathode filament 34 is supported as at 35 on this support 54 and extends about it in opposite helical coils 50 and in spaced relation and is connected to the bottom wall 50 as at 55 and connected to the end wall 51 as at 56. The outer cylindrical wall 42 is the same as heretofore described in connection with Fig. 1.

55 In the use of the construction shown in Figs. 2 and 3, energy is supplied to the filament for heating it and for electron emission through the leads 15a and 16a, while the filament is connected to the capacitance 48, 49, 42 and will 60 conduct the high frequency current from the cathode filament to some external circuit.

In the showing in Fig. 4 the cathode shield 26 is as shown in Fig. 1 except there is provided a central opening 60 in the end wall 28 through which there extends a heating filament 61 in generally U-shaped formation with its ends 62 and 63 connected to the leads 64 and 65 extending through the stem press. A cathode sleeve 66 surrounds the heating filament 61 and is insulated therefrom. The bottom of this cathode sleeve is electrically connected to the bottom wall 28 by one or more tabs 67, and the support 16 may conduct direct current or low frequency alternating current to the cathode for its emission of electrons.

In the various showings which I have above described, any base may be utilized, but it is often convenient to utilize the outer cylindrical member as a base and I have shown at 68 in Fig. 5 this cylindrical member as extending downwardly a sufficient extent to provide a base while a wafer 69 is held in a recess 70 and in turn supports the contact pins 71 and 72 to which the leads from the stem are connected.

In Fig. 6 I have carried this outer cylindrical member now designated 73, upwardly and, through some insulating spacing part 74, have mounted a concentric tube 75 which may form one of the leads of a shielded arrangement. In this case I have connected the plate 20 to the inner concentric member 75 by means of the connection 76 while the grid lead 77 may extend through an opening 78 in the outer tube for a short lead to the circuit in which it is located.

I claim:

1. A radio frequency tube comprising a dielectric envelope enclosing electrodes one of which is a cathode element, heating current leads connected to said element and providing a continuous metallic circuit only for said cathode element, cylindrical inner and outer metallic members on either side of said envelope providing an electrical capacitance, means connecting the inner member to said cathode element whereby the outer member may be connected to an external circuit to conduct ultra high frequency current from said element through the dielectric envelope.

2. A radio frequency tube comprising a dielectric envelope enclosing electrodes one of which is a cathode element, a continuous metallic circuit for conducting heating current to said element and constituting the only lead in means for said element, inner and outer cylindrical metallic members on either side of said envelope providing an electrical capacitance, means connecting the inner member to said cathode element whereby the outer member may be connected to an external circuit to conduct ultra high frequency current from said element through the dielectric envelope, one of said members being interposed in the heating current circuit.

3. A radio frequency tube comprising a dielectric envelope, a cathode element therein, heating current leads connected to said element, inner and outer cylindrical metallic members on either side of said envelope providing an electrical capacitance, means connecting the inner member to said cathode element whereby the outer member may be connected to an external circuit to conduct radio frequency current from said element through the dielectric envelope, said outer member comprising the base for the tube.

4. A radio frequency tube comprising a dielectric envelope, a cathode element therein, heating current leads connected to said element, inner and outer cylindrical metallic members on either side of said envelope providing an elec-

trical capacitance, means connecting the inner member to said cathode element whereby the outer member may be connected to an external circuit to conduct radio frequency current from said element through the dielectric envelope, said outer member comprising the base for the tube, and shaped to form a mounting means.

5. A radio frequency tube comprising a dielectric envelope, a cathode element therein, heating current leads connected to said element, inner and outer cylindrical metallic members on either side of said envelope providing an electrical capacitance, means connecting the inner member to said cathode element whereby the outer member may be connected to an external circuit to conduct radio frequency current from said element through the dielectric envelope, said outer member extending along the tube longitudinally thereof and an inner concentric line conductor connected with said outer member.

20 6. A radio frequency tube comprising a dielectric envelope, a cathode element therein, heating current leads connected to said element, inner and outer cylindrical metallic members on either side of said envelope providing an electrical capacitance, means connecting the inner member to said cathode element whereby the outer member may be connected to an external circuit to conduct radio frequency current from said element through the dielectric envelope, said outer member extending along the tube longitudinally thereof and an inner concentric line conductor connected with said outer member and another of the elements of the tube being connected to said inner concentric line conductor.

35 7. A radio frequency tube comprising a dielectric envelope enclosing electrodes one of which is a cylindrical metallic member on the inner side of said envelope and a cylindrical metallic member on the outer side of said envelope providing an electric capacitance, a metallic wall extending inwardly from the inner of said members, a cathode element connected to and supported by said wall, said outer member being adapted to be connected to an external circuit to conduct an ultra high frequency current from said element through the dielectric envelope.

40 8. A radio frequency tube comprising a dielectric envelope enclosing electrodes one of which is a cylindrical metallic member on the inner side of said envelope and a cylindrical metallic member on the outer side of said envelope providing an electrical capacitance, a metallic wall extending inwardly from the inner of said members, a cathode element connected to and supported by said wall, said outer member being adapted to be connected to an external circuit to conduct an ultra high frequency current from said element through the dielectric envelope and continuous metal heating current leads extending from said element.

RICHARD S. BRIGGS.
